CLAIM

The ornamental design for a combination bathtub and shower unit and seat for handicapped and elderly persons, as shown and described.

DESCRIPTION

FIG. 1 is a right front perspective view of a combination bathtub and shower unit and seat for handicapped and elderly persons embodying my new design; and, FIG. 2 is a left front perspective view thereof.

The back, not shown, is substantially plain and unornamented.

Those portions shown in broken lines are for environmental and illustrative purposes only and form no part of the claimed design.
